UNITED STATES PATENT OFFICE.

FREDERICK HAMILTON, OF PROVIDENCE, RHODE ISLAND.

DESIGN FOR A LENS-CLIP.

45,630.

Specification for Design.

Patented Apr. 21, 1914.

Application filed May 24, 1912. Serial No. 699,567. Term of patent 14 years.

To all whom it may concern:

Be it known that I, FREDERICK HAMILTON, a citizen of the United States, residing at Providence, in the county of Providence and State of Rhode Island, have invented a new, original, and ornamental Design for Lens-Clips, of which the following is a specification, reference being made to the accompanying drawings, forming a part thereof.

My invention relates to improvements in lens clips or attachments and the object of my invention is the provision of an improved design for a lens clip which will be of attractive and ornamental appearance and will add to the desirability and attractiveness of eyeglass or spectacle mountings embodying the said clip.

Figure I represents a plan view of my improved design for lens clip, particular attention being called to the graceful outline of the said clip and to the segment shaped aperture formed in one end thereof. Fig. II represents an edge view thereof.

I claim:

The ornamental design for a lens clip as shown and described.

In testimony whereof, I affix my signature in the presence of two witnesses.

FREDERICK HAMILTON.

Witnesses:

R. A. DANIELS,
H. B. HAMILTON.
